Rene Gravine

UNITED STATES PATENT OFFICE.

BARTHolemew E. McSHEEHY, OF HUNTINGDON, PENNSYLVANIA, ASSIGNOR TO J. C. BLAIR COMPANY, OF HUNTINGDON, PENNSYLVANIA, A CORPORATION OF PENNSYLVANIA.

FOLDING PAPETERIE.

Application filed October 23, 1918. Serial No. 259,417.

To all whom it may concern:

Be it known that I, BARTHolemew E. McSHEEHY, a citizen of the United States of America, residing in Huntingdon, in the county of Huntingdon and State of Pennsylvania, have invented certain new and useful Improvements in Folding Papeteries, of which the following is a specification.

The object of my invention is to provide 10 a folding papeterie which can be cheaply made and affords a practical and compact, portable container for writing paper and envelopes, and also serves the purpose of a support or lap table which can be conveniently used for correspondence.

The structure is intended chiefly for soldiers and travelers, being designed to permit of carrying a supply of envelopes and paper in a small, neat package, which may 20 also serve to hold the paper in convenient position for writing.

An additional purpose is to make the structure sufficiently cheap so that it can be used in place of the ordinary box container and 25 sold at a price which would ordinarily permit it to be discarded when the supply of paper and envelopes is exhausted.

An additional object contemplated by the invention is to retain the sheets of paper and 30 envelopes independently of one another, and securely held, while also permitting immediate access to either the envelopes or paper, without disturbing the other.

The invention consists, briefly, of an envelope-containing section and a sheet-holding section, the two being preferably formed integrally and united by a hinge portion. In the preferred arrangement, the writing sheets are attached to the sheet-holding section in the form of a writing pad or tablet, the back of which is secured to the sheet-holding section, although this may be accomplished in other ways, as by arranging a series of loose writing sheets within a 45 pocket or case which would be attached to the sheet-holding section. The envelope-containing section is provided with a plurality of envelope pockets which are preferably open at both ends, to afford a cheap 50 and simplified construction, and having one

side attached to the envelope-containing section. The latter includes a back which is provided with an extension that is adapted to overlie the outer open ends of the envelope pockets, and also a portion of their exposed sides, and this arrangement holds the envelope pockets securely in place and also affords a slight and cheap construction. In order to strengthen the device and make it durable enough for the purposes required, 55 without unduly increasing its cost of manufacture, I prefer to reinforce the hinge portion by means of a strip of fabric or similar material, placed over and attached to the cardboard from which the other parts are 60 preferably constructed. The repeated bending of the two sections with reference to each other would quickly separate the cardboard along such a folded line, unless a very heavy thickness were used, and by taking 65 advantage of such a reinforcing means, a much thinner and cheaper grade of cardboard can be used for the body of the folder.

To these and other ends, the invention 70 consists in certain improvements and combinations of parts, all as will be hereinafter more fully described, the novel features being pointed out in the claims at the end of the specification.

Figure 1 is a perspective view illustrating 80 a preferred embodiment of the invention in its unfolded position;

Fig. 2 is a perspective view, showing the sections folded one upon the other, with a corner portion broken away;

Fig. 3 is a sectional view, greatly enlarged on line 3—3 of Fig. 1;

Fig. 4 is a sectional view on line 4—4 of Fig. 2;

Fig. 5 is a sectional view on line 5—5 of Fig. 2;

Fig. 6 is a perspective view showing a slightly modified form of the invention, and

Fig. 7 is a sectional view on line 7—7 of Fig. 6.

In the preferred form illustrated in Figs. 1 to 5, inclusive, A designates the sheet-holding section and B is the back portion of the envelope-containing section which is 100

connected to the sheet-holding section A by a central hinge portion C, permitting the two sections to be folded one upon the other from the position shown in Fig. 1 to that shown in Fig. 2, and it will be seen that when folded, the device is extremely compact and can be conveniently carried about or packed in a small space.

In the illustrated arrangement, the writing paper is in the form of a pad or tablet D, the back of which, E, is glued, or otherwise fixedly attached to the sheet-holding section A. In order to protect the edge of the pad D, as well as to present a neat and slight appearance when the device is folded, I employ a flap, including a vertical portion F, adapted to overlie the adjacent edge of the tablet D, and a horizontal portion F', adapted to overlie the adjacent portion of the top of the writing pad when the parts are folded, as illustrated in Fig. 2.

The envelope-containing section is provided with a plurality of envelope pockets 25 designated by G and G'. Each of the envelope pockets is preferably open at both ends and consists of a single strip of cardboard bent upon itself and attached along its meeting edges, as shown in Fig. 5. The 30 pockets G and G' have their lower sides secured to the back portion B of the envelope-containing section by glue or otherwise, and afford two separate and distinct compartments for the envelopes. The inner 35 ends of the pockets G and G' extend toward the central hinge portion C, preferably terminating at a slight distance therefrom, while the outer ends of the pockets are closed by an extension B' which is bent upwardly from the back portion B of the envelope-containing section and has its extremity B² overlying and attached by gluing or otherwise to parts of the upper sides of the pockets G and G'.

From the structure thus far described, it will be apparent that the envelopes and paper are independently accessible, and are amply housed and protected under all conditions. Furthermore, the device when unfolded, as in Fig. 1, can conveniently be placed upon the knee or lap and affords an efficient support or table for the paper itself, when writing upon the latter. It is, of course, essential that the folder last and be serviceable until the supply of paper and envelopes is exhausted, and with this in view, I provide the hinge portion C with a reinforcing portion H of suitable fabric, which is secured over the hinge portion C and the adjacent parts of the sections A and B, as shown in Fig. 4, and also is turned interiorly and secured against parts of the corresponding inner surfaces, as shown by H' in Fig. 1. By thus reinforcing the hinge portion, the parts can be repeatedly folded

and unfolded, at least as long as the supply of paper and envelopes would usually last, without becoming torn or separated, and at the same time it is possible to make use of a comparatively thin and correspondingly cheap cardboard for the body of the folder.

In some cases, it may be preferable to have the writing sheets in loose form instead of in tablet form, and to answer such requirements, I may further modify the 75 structure as shown in Figs. 6 and 7. According to this arrangement, the paper in loose sheets or other suitable form, is arranged within a pocket or container I, open at its inner edge to receive the paper, as shown by I'. The pocket I would preferably extend from one end of the sheet-holding section to the other to accommodate a long sheet, and would conveniently be formed and attached as the envelope pockets 80 G and G' previously described. That is to say,—the outer open side of the container I would be closed by an extension J on the bottom section, overlying the side of the pocket I and a part of its upper surface, to 90 which latter it may be attached by gluing or otherwise. This modified form permits either the paper or envelopes to be withdrawn toward the central or hinge portion of the folder, while the upper surface of the 95 pocket or container I may be utilized as a writing surface, if desired.

What I claim is:

1. A foldable papeterie comprising an envelope containing section and a sheet-holding section connected thereto by a hinge portion, the envelope-containing section consisting of a back portion, a plurality of open-ended envelope pockets attached to the back portion, the inner open ends of the pockets being located near said hinge portion, and an extension on the back portion overlying the outer open ends and parts of the top faces of the envelope pockets and attached to said faces to close said outer open ends. 100

2. A foldable papeterie comprising an envelope-containing section, a sheet-holding section connected thereto by a hinge portion, a writing tablet secured to the sheet-holding section, a flap at one edge of the sheet-holding section adapted to overlie the adjacent edge and top of the writing tablet, the envelope-containing section consisting of a back portion, a plurality of open-ended envelope pockets attached to the back portion, the inner open ends of the pockets being located near said hinge portion, and an extension on the back portion overlying the outer open ends and parts of the top faces of the envelope pockets and attached to said faces to close said outer open ends. 115

3. A foldable papeterie, comprising an envelope containing section and a sheet-holding section connected thereto by a hinge portion, which is integral with a back por- 120

tion common to both sections, the envelope containing section comprising open ended envelope pockets attached to the back portion, and an extension on the back portion over-
lying the outer open ends and parts of the top faces of the envelope pockets and attached to said faces to close said outer open

ends, said papeterie when in folded condition providing a rectangular packet free from protuberances.

In witness whereof, I have hereunto signed my name.

BARTHOLOMEW E. McSHEEHY.
